US00D855092S

(12) **United States Design Patent** (10) **Patent No.:** **US D855,092 S**
(45) **Date of Patent:** **** Jul. 30, 2019**

(54) **WELDING MACHINE**

(71) Applicant: **SHANGHAI HUGONG ELECTRIC (GROUP) CO., LTD.**, Shanghai (CN)

(72) Inventors: **Zhenyu Shu**, Shanghai (CN); **Zhiqiang Li**, Shanghai (CN)

(73) Assignee: **SHANGHAI HUGONG ELECTRIC (GROUP) CO., LTD.**, Shanghai (CN)

(**) Term: **15 Years**

(21) Appl. No.: **29/633,131**

(22) Filed: **Jan. 12, 2018**

(51) LOC (11) Cl. **15-09**

(52) U.S. Cl.

USPC **D15/144**

(58) **Field of Classification Search**

USPC ..... D8/29.1, 30; D13/101, 109, 110, 112, D13/116, 122, 123, 133, 144, 184; D15/144, 144.1, 144.2, 145, 146 CPC ... B23K 9/00; B29C 65/1432; B29C 65/1467; B29C 65/4815; B29C 65/5042; B29C 65/5092; B26C 66/1142; B26C 66/43; B26C 66/435; B26C 66/73185; B26C 66/73921

(57) **CLAIM**

The ornamental design for a welding machine, as shown and described.

DESCRIPTION

FIG. 1 is a perspective view of the design for the welding machine;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines are for the purposes of illustrating portions of the welding machine and form no part of the claimed design.

1 Claim, 7 Drawing Sheets
